UNITED STATES PATENT OFFICE

110,833

DESIGN FOR A TIRE

Irving Jay Fain, Providence, R. I.

Application October 2, 1937, Serial No. 71,923

Term of patent 3½ years

To all whom it may concern:

Be it known that I, Irving Jay Fain, citizen of the United States, residing at Providence, in the county of Providence and State of Rhode Island, have invented a new, original, and ornamental Design for a Tire, of which the following is a specification, reference being had to the accompanying drawing, forming part thereof.

In the drawing:

Fig. 1 is a plan view of a section of a tire, showing my new design;

Fig. 2 is a cross-sectional view taken along line 2—2 of Fig. 3; and

Fig. 3 is a side view of the design shown in Fig. 1.

I claim:

The ornamental design for a tire, as shown.

IRVING JAY FAIN.
